HAT

Frank H. Lee, Danbury, Conn.

Application October 31, 1934, Serial No. 750,884

3 Claims. (Cl. 2—181)

This invention relates to hats and more particularly to improvements in sweat bands therefor.

Among the objects of the invention may be noted the provision of a hat of improved construction; the provision of a hat having a sweat band of improved construction and design; the provision of a hat and sweat band construction which is comfortable to the wearer, durable and rugged in use, and which overcomes the disadvantages of known hat and sweat band constructions; the provision of a sweat band for hats characterized by novel design, ease in application to the hat, and comfort to the wearer of the hat to which it is applied; the provision of a sweat band which may be applied with equal facility to both felt and straw hats; the provision of a simple and improved method of hat construction; and the provision of an improved method of securing a sweat band to the hat.

Other objects will be in part obvious and in part hereinafter pointed out in connection with the following analysis of this invention wherein is described and illustrated a preferred mode of carrying out the present invention, together with possible modifications thereof.

In the drawing—

Fig. 1 is a bottom perspective view of a hat and sweat band construction in accordance with the present invention;

Fig. 2 is a longitudinal section through a hat and sweat band as illustrated in Fig. 1;

Fig. 3 is an enlarged section illustrating the configuration and the mode of connection of a portion of the sweat band to the hat;

Fig. 4 is a detail further illustrating the features shown in Fig. 3;

Fig. 5 is a face view of the developed sweat band blank, in accordance with the present invention.

As conducive to a clearer understanding of the improved construction and practice about to be described in relation to prior construction and practices, it may be noted that in conventional sweat bands and according to the known practices of securing such to the hats, sweat bands in prior use are generally of two kinds. The first kind or class includes sweat bands which are stitched along their lower edge and throughout their entire periphery to the hat at or about the junction of the crown and brim of the hat. Such securing is effected by means of a line of stitching which acts both to secure the lower edge of the band to the hat and also to whip the lower portion of the band into the hat along its se-

cured lower portion. Such form of securing of the band to the hat leaves exposed portions of the securing thread, and such exposed portions of the thread contact with the head of the wearer and particularly the forehead, with the result that the thread of the stitching acts to chafe and/or cut into the skin of the forehead and is generally uncomfortable.

Certain attempts have been made to cure the disadvantages of the edge stitching mode of securing of the sweat band to the hat and such have resulted in the development of the flange type of sweat band. Such latter type of band comprises a band proper which engages the head, and an integral upwardly extending securing strip or flange disposed outwardly of the lower portion of the band and extending throughout the entire periphery thereof. Securing between the hat and the band is effected by a line of stitching between the flange and the lower crown portion of the hat proper. While contact between the head and the threads of the stitching which acts to secure the band to the hat is obviated by such an arrangement, the flange type of sweat band results in other disadvantages and discomforts to the wearer, among which may be noted the tendency of the band to cling to the head, with the result that the sweat band is pulled out of the hat when the hat is lifted and/or removed from the head. The sweat band remains in such disturbed condition until manually reset and is a source of annoyance to the wearer, as the pulled-out band must be reset before the hat is replaced on the head.

Certain attempts have also been directed to the provision of sweat bands which are edge-stitched to the under brim portion of the hat outwardly of the junction between the crown and brim thereof, with the band extending smoothly along the inner brim portion and thence into the crown and upwardly thereof. While in the latter form of construction and securing, the head is protected from contact with the stitching, the band has the same tendency to cling to the head as in the case of the flange type of band and securing, and pulls out as the hat is lifted and/or removed from the head and must be manually reset prior to replacement of the hat on the head.

According to the present invention, I overcome the disadvantages of the aforesaid constructions and practices by the provision of a sweat band of novel design and application, of which the following is a description of the preferred form of the invention.

Referring to the drawing, reference character 10 indicates generally a hat including a crown 11 and a brim 12, the said crown and brim being joined along the junction line 13. It will be understood that the hat as shown is illustrative of a conventional hat of approved construction and material, and I do not intend to be limited with respect thereto as the sweat band to be described is applicable for use with hats generally, such as felt hats, straw hats, and the like.

Referring now to my improved sweat band construction, such comprises a band 15 of approved material, such as leather, of a length, depth and configuration that when the abutting ends 16a, 16b, are secured together and the band inserted in the crown, the band will assume and conform to the generally oval shape of the crown. Preferably, the band is so formed that when applied to the hat it is slightly conical whereby the upper portion of the band extends inwardly from the inner wall of the hat crown relative to the lower portion of the band, thus to adapt itself to the head of the wearer and to have a cushioning effect.

A band blank in accordance with the present invention is illustrated in Fig. 5, and comprises an elongated band having its relatively top and bottom edges cut or otherwise formed along substantially concentric arcs whereby the band may adapt itself to the "scope" of the hat, the end portions 17 of which are of uniform depth, with the intermediate portion 18 being of greater depth by about $\frac{1}{8}$ of an inch, although such dimensioning may vary within reasonable limits. Such portion 19 of increased depth thus forms a tongue or flange depending from the normal lower edge 20 of the band, the lower edge of the flange following generally the curvature or "scope" of the band proper. The length of the flange 19, that is, the distance that it extends along the band or peripherally thereof, when the ends 16a, 16b of the band are secured together, is such that it extends across the forehead of the wearer and approximately from temple hair line to temple hair line, this distance being of the order of 7 to 9 inches, depending on the head size of the hat and being subject to variation within reasonable limits.

In preparing the so-formed blank for application to the hat, the tongue or flange 19 is folded over on the body portion of the blank 15 and on a line of fold that forms a substantial continuation of the curved or "scoped" edges 20 of the blank. With the blank in the position illustrated in Fig. 5 and looking at the finished face of the band, the folding is relatively rearward. Preferably, the folding operation is effected by running the band between rollers which act to break over and fold the flange rearwardly and to crease the band along its line of fold. In order to cause the portion of the band adjacent the line of fold to fit snugly against the head, the folded over edge of the band is beveled outwardly (Figs. 3 and 4) as by running the folded band through beveling rollers which cause the lower portion of the band adjacent the folded edge to be turned relatively outwardly whereby the flange sets snugly against the body portion of the band. The ends 16a, 16b, of the leather are thereupon secured to each other and preferably in abutting relation as by stitching, and the band is ready for attachment to the hat.

From the positioning of the flange or tongue 19 intermediate the ends of the band and its

symmetrical relation with respect to the transverse center line of the band (Fig. 5), it will be evident that the flange is disposed along the relatively front portion of the band and along the forehead contacting portion thereof, it being understood that the secured ends 16a, 16b, of the band are usually disposed to the rear of the hat whereby to engage the back of the head. 5

The lower edges 20 of the end portions 17 of the band are formed in the conventional manner for stitching to the hat as by the known edge stitching practices. It will be understood that one face of the band is preferably of finished appearance, and such face may be suitably sized and/or the material of the band suitably treated throughout to protect the band or the head contacting face thereof from staining or contamination due to the absorption of perspiration, skin oils, and the like.

Considering now the manner of applying the band as above described to a hat, such as the hat 10, Figs. 1 and 2, the oval band resulting from the operations aforesaid is relatively inverted, and the securing flange portion 19, turned to unfolded position, may be disposed interiorly of the crown 11 of the hat. The depth of insertion of the flange into the crown as aforesaid is substantially the depth of the flange, and preferably slightly less than such depth, so that when the band proper 15 is folded and set into the crown of the hat, its beveled edge extends slightly below the junction line 13 of the hat crown and brim. The arrangement of insertion is further such that the finished or hat contacting surface of the band faces outwardly, with the band portion proper extending downwardly or below the under brim surface, as indicated in dotted lines, Fig. 3. As to the positioning of the flange about the periphery of the hat crown, the flange is so positioned that it extends across the front head portion of the hat and symmetrically with respect to the longitudinal center line thereof.

With the so positioned flange suitably held against the inner wall of the crown and adjacent the brim, a line of stitching 22 (Figs. 3 and 4) is passed through the material of the lower crown and into the flange 19 whereby to secure the flange in the position aforesaid. Preferably, the stitches are not passed through the entire thickness of the flange but, rather, are passed partly therethrough so as to be caught by the material of the flange, as indicated in Fig. 4. Thus, the stitching is substantially concealed when viewing the flange from within the hat crown, and in this manner the thread of the stitching is maintained out of contact with the head and thus there is little possibility of absorption by the threads of perspiration, skin oils, and the like. 60

Upon completion of the stitching of the flange to the inner crown portion of the hat as aforesaid, the band proper 15 is folded into the crown and about the line of fold with respect to the flange 19 which is a substantial continuation of the bottom edge 20 of the end portions 17 of the sweat band proper. When the band is so folded into the crown, it will be apparent that the flange 19 is disposed intermediate the inner crown surface and the band proper 15, and that the beveling of the lower edge of the band causes said band to lie closely against the hat at its junction portion 13, whereby the band may snugly fit the head. Thereupon, a line of stitching 23 is passed through the edge 20 of the end portions of the 75

sweat band and the material of the hat whereby to secure such edge portions to the hat at about the junction line 13 of the crown 11 and brim 12, as is conventional, and in such manner that 5 said edges 20 extend slightly on to the under brim surface. Such line of stitching 23 further acts to whip the lower edge of the end portions 17 of the band into close contact with the hat along its junction line 13 whereby the sweat band 10 conforms to the generally oval shape of the hat.

As will be understood, the hat is provided with an ornamental exterior band 25 which is applied in the usual manner, and such band 25 acts to obscure from view the line of stitching 22, as 15 well as to provide an ornamental and neat appearance to the hat, as is well understood. The hat may further be provided with an inner tip or crown lining 26, if desired.

By the aforesaid construction of the sweat 20 band and its mode of application to the hat, the sweat band is held to the hat along its front or forehead contacting portion by the line of stitching 22 which functions to secure the flange 19 to the lower portion of the hat crown. The thread 25 of such stitching in nowise contacts with the skin of the forehead and, further, the double thickness of material formed by the sweat band and the flange acts as a cushion. In such manner, comfort to the wearer is assured, especially 30 because no thread or line of stitching can cut or chafe the skin of the temples and/or forehead as would be present if the sweat band were stitched to the hat across the front or forehead engaging portion by the conventional edge 35 stitching practices.

Throughout the side and back portions of the head, which are generally protected by hair, the sweat band is secured by the edge stitching 23. Such edge stitching in contact with the head 40 portions protected by hair is not only not objectionable but is desirable, whereby to overcome the tendency of the sweat band to cling to the rear part of the head and to pull out of the hat when the hat is being raised and/or removed, which latter tendency accompanies the 45 use of the flange type of securement to secure the rear portion of the sweat band to the hat.

It will be evident from the foregoing that a sweat band in accordance with the foregoing and 50 applied by the practice of the present invention, overcomes the disadvantages attendant to the use of both the flange method of securing a sweat band and to the use of the edge stitching method of securing the sweat band, throughout the entire 55 crown periphery. The resulting arrangement is such that comfort and convenience to the wearer of the hat to which the sweat band is applied is assured, and at the same time the continual annoyances resulting from the sweat band pulling out of the hat are obviated. Further, the aforesaid hat and sweat band construction is of a rugged and durable nature. It will also be 60 obvious to those skilled in the art that the sweat band in accordance with the present invention is capable of ready and inexpensive manufacture by known methods and practices and may be

readily applied to the hat without substantial departure from known practices.

Without further analysis, the foregoing will 5 so fully reveal the gist of this invention that others can by applying current knowledge readily adapt it for various applications without omitting certain features that from the standpoint of the prior art fairly constitute essential characteristics of the generic or specific aspects of this invention, and therefore such adaptations 10 should and are intended to be comprehended within the meaning and range of equivalency of the following claims.

I claim:

1. In a hat construction, the combination of 15 a hat having a crown and a brim, a sweat band disposed interiorly of the crown and adjacent the brim, the band having an upturned bottom flange disposed between the inner crown surface and the band and folded with respect to the band 20 along a line of fold which is a continuation of the normal bottom edge of the band, the flange extending along the forehead engaging portion only of the band, means for securing the flange to the hat crown, and means for securing the 25 normal bottom edge of the portions of the band engaging the sides and back of the head to the hat at about the junction of the crown and brim thereof.

2. In a hat construction, the combination of 30 a hat having a crown and a brim, a sweat band disposed interiorly of the crown and adjacent the brim, the band having an upturned bottom flange disposed between the inner crown surface and the band and folded with respect to 35 the band along a line of fold which is a continuation of the normal bottom edge of the band, the flange extending along the forehead engaging portion only of the band, the band and flange being beveled outwardly along the line of fold 40 between the band and flange, means for securing the flange to the hat crown, and a line of stitching for securing the normal bottom edge of the portions of the band which engage the sides and back of the head to the hat at about 45 the line of junction between the crown and brim thereof, said line of stitching being operative to position the band adjacent its so secured edge in close contact with the hat along its junction line as aforesaid. 50

3. As a new article of manufacture, a hat sweat band comprising an elongated band of leather, the relatively top and bottom edges of which are formed along substantially concentric arcs, the band intermediate its ends having an arcuate 55 flange and the flange being folded with respect to the body portion of the band on a line of fold which is substantially a continuation of the bottom edge of the end portions of the band which are devoid of such flange, the length of the 60 flange being substantially the distance across the forehead of the wearer of the hat to which the band is applied, and the band and flange being bevelled outwardly along the aforesaid line of fold. 65
